(57) **CLAIM**

The ornamental design for a tire tread as shown and described.

DESCRIPTION

FIG. 1 is a perspective view of a hand truck tire showing our new design;

FIG. 2 is a front elevational view thereof;

FIG. 3 is side elevational view of the right side thereof, the opposite side being identical thereto; and,
FIG. 4 an enlarged fragmentary side perspective view thereof.

The broken lines defining the tire sidewall and inner bead are for illustrative purposes only and form no part of the claimed design.
